UNITED STATES PATENT OFFICE.

JOHN V. BUCKLE, OF SALT LAKE CITY, UTAH, ASSIGNOR OF ONE-HALF TO EDGAR E. DUSTIN, OF SALT LAKE CITY, UTAH.

DRINK-MIXER.

1,340,849.

Specification of Letters Patent. Patented May 18, 1920.

Application filed December 1, 1919. Serial No. 341,706.

To all whom it may concern:

Be it known that I, JOHN V. BUCKLE, a citizen of the United States, residing at Salt Lake City, in the county of Salt Lake 5 and State of Utah, have invented certain new and useful Improvements in Drink-Mixers, of which the following is a specification.

My invention relates to agitating machines, and has for its object to provide a means whereby one or more drinks may be 10 mechanically mixed in separate receptacles at the same time.

This object I accomplish with the device 15 illustrated in the accompanying drawings in which similar letters and numerals of reference indicate like parts throughout the several figures and as described in the specification forming a part of this application 20 and pointed out in the appended claims.

In the drawings in which I have shown a substantial embodiment of my invention, Figure 1 is a front elevation of the device with a glass receptacle therein shown in 25 dotted lines. Fig. 2 is an end elevation of the same. Fig. 3 is a vertical section of the supporting standard on line 3—3 of Fig. 1. Fig. 4 is a plan view of the receptacle holding means. Fig. 5 is a plan and edge view 30 of one of the agitating arms. Fig. 6 is a plan view of the horizontal shaft with a section through its bearing to show the means for preventing end thrust. Fig. 7 is a side elevation of my drink mixer, showing two 35 of the units in full lines and a portion of another unit in dotted lines, parts of the base plate, motor standard and motor cut away.

My invention is principally for use in 40 drink dispensing places, and especially for quickly and thoroughly mixing the ingredients for such drinks as malted milk, and the like, and wherein the agitating elements are moved by a small electric motor which 45 is only energized when one or more of the agitators are in use, and from which motor, all of the other parts of the device are insulated. One special feature is to provide an economical device whereby one or more 50 drinks may be separately mixed at one time. Another feature is to provide a mixer which will mechanically and thoroughly mix the liquid without spilling any.

The present invention consists of a base 55 plate A, preferably made of onyx or mar-

ble and on which the other parts of my device are mounted. The electric motor B is fastened on the upper end of a hollow standard C. A sleeve 1, made of insulating material, has one end thereof secured on the 60 motor shaft D. Another hollow standard 2 is vertically mounted on and firmly secured to said base plate A, and within which standard is longitudinally operated the contact plunger 3 and the agitator support. Electric wires a and b are carried 65 in the said standard C and with leads on the lower side of said base plate A to an opening or hole in said base plate below the lower end of said standard 2, where said 70 wires are fastened in spaced apart relation to each other and act as contact posts against which the contact member 5 on the end of said plunger 3 is held to form an electric circuit in which is included a source of electric energy, not shown, with which the said 75 wires a and b are connected. The said agitator support consists of a sleeve 4 slidably and rotatably operated within said standard 2, and normally held in an extended position as shown in dotted lines in Fig. 3 by 80 the spiral spring 6 carried around said plunger 3. One end of said spring 6 is fastened to a thimble 7 that in turn is secured in the lower end of said standard 85 2, while the other end of said spring bears against a collar sleeve 8 which is in turn fastened in the upper end of said sleeve 4. A yieldingly held dog 9 is pivoted in a bearing bracket 10 which is secured on the 90 upper portion of said standard 2, and said dog is formed to engage the base of a thumb piece 11, that is secured on the upper end of said plunger 3. An insulating plug 12 is fastened on the lower end of said plunger 95 3 and said contact 5 is fastened in or to said plug, thereby insulating said contact from all of the parts of my device except when it is brought in contact with said wires a and b. A Y-shaped bearing member 13 is secured on the upper end of said sleeve 4 by the said thumb piece 11 being screwed on the upper portion of said plunger 3 and a shoulder 14 on said plunger bearing against the lower side of said collar 105 sleeve 8, which in turn bears against the lower side of said Y-shaped bearing member 13. The agitator shaft 15 is carried and journaled in said Y-shaped bearing member and is thereby held vertically and 110

rotatably in position. A friction member 16 is fastened on said agitator shaft by the jam nut 17. Agitating arms 18 are secured on and for rotation with said agitator shaft 5 15 one of which is positioned near or on the lower end of said shaft with its blades inclined to move the liquid upwardly and outwardly in a mild way while the other is positioned above the lower end of said shaft 10 and with its blades inclined to move the liquid downwardly as well as outwardly. A receptacle holder 19 is fastened at one end to said standard 2 and is made of spring material to yieldingly retain a receptacle 20 15 when placed therein and resting on said base plate A. A horizontal shaft 21 is mounted for rotation in the said bearing bracket 10 and with one end secured in the insulating sleeve 1. A friction disk 22 is 20 secured on and made to rotate with said shaft 21 by the pin 23 which is passed through the hub of said friction disk then through said insulating sleeve 1 and through said shaft 21. I designate all of 25 my device from the line $x-x$ toward the right in Fig. 1, an agitating unit, and I provide as many agitating units as may be desired in order that more than one receptacle full of liquid may be mixed at the 30 same time, by extending the base plate A, or adding another plate and duplicating all parts of my device from the line $x-x$. To do this a hole 24 is provided in the free end of each of said horizontal shafts 21, and 35 the horizontal shaft 21 of the added unit is secured on the end of the first or any added shaft 21 by a duplication of pin 23, and connecting the wires a and b of each added unit with the wires of the preceding 40 unit at the bolts 25 shown in Fig. 3. The electric connection may be made by the operator of any unit by throwing his unit into mixing position. The different elements of the second unit of my device are indicated 45 by the same respective reference numerals used in the first unit with the addition of a prime mark ("') to indicate that it is an element of the second unit, and as far as shown in Fig. 7 the reference numerals are 50 respectively given the double prime mark ("'') thus to indicate that they belong to the third unit.

The operation of my device is as follows:

With a source of electric energy provided 55 to drive the motor B when it is brought into the circuit, and with the agitating means turned in the position shown in dotted lines in Fig. 3, the contact member 5, insulating plug 12 and lower end of the plunger 3 60 will be about on a level with the upper edge of the receptacle 20; while the agitating shaft and lower agitating arm 18 will be above the plane of the upper edge of the mixing receptacle 20 thus allowing free 65 swinging of the agitating members. When

the said mixing receptacle 20, preferably made of glass, with the desired unmixed contents is placed within the holder 19 and resting on the said base plate A, the operator will swing the agitator into mixing 70 position, with the shaft 15 vertically over the receptacle, this will bring the friction member 16 in contact together with the friction disk 22, then by pushing down the plunger 3, with the agitating means, the 75 contact 5 will be forced between the end portions of the wires a and b , similar to a knife switch, and the electric circuit will be completed and the motor with the shaft 21 will be rotated. The dog 9 will engage 80 the flange portion of the thumb piece 11 and hold the agitating elements in the position shown in Fig. 1. With the friction elements 16 and 22 engaged, rotation will be imparted to said arms 18 and the liquids 85 thoroughly mixed without any tendency to throw the contents of the receptacle over its edge. By pressing down on the thumb portion of the dog 9 to release it from its engagement with said thumb piece 90 11, the spring 6 will move the agitating elements vertically upward and the electric circuit will be broken. The agitating means may then be swung from over the receptacle to the position shown in Fig. 3. If another 95 operator is using another unit farther away from the motor he may complete the electric circuit by making a contact with his contact plug 5 and wires a and b , and the removal of any contact 5 from between the 100 wires a and b will affect only the unit so operated. By using ball bearings 26 with a 105 slidable race plate 27, and adjustable collar 28 I am able to hold the friction elements 22 and 16 without end thrust on the motor shaft D.

I thus provide new and novel agitating means to prevent spilling of the contents of the receptacle; new and novel means for rotating the agitator; as well as new and 110 novel means for economically and mechanically agitating one or more liquid mixtures at the same time.

Having thus described my invention and its operation I desire to secure by Letters 11 Patent and claim:—

1. A drink mixer comprising an electric motor having a horizontal shaft and mounted on a base plate; one or more agitating units mounted on said base plate and detachably connected with the shaft of said motor, each of said units consisting of a supporting vertical standard; a sleeve slidable and rotatable therein; a plunger operable within said sleeve; means on said plunger to 12 make and break an electric circuit in connection with said motor; a vertical agitating shaft supported on and operable with said sleeve; a horizontal shaft journaled for rotation at one end on said vertical stand- 13

- ard and detachably connected with the shaft of said motor at its other end; and means to operatively connect said vertical shaft with the last mentioned horizontal shaft.
- 5 2. A drink mixer comprising an electric motor having a horizontal shaft and mounted on a base plate; one or more agitating units mounted on said base plate and detachably connected with the shaft of said
- 10 motor, each of said units consisting of a supporting vertical standard; a sleeve slidable and rotatable therein; a plunger operable within said sleeve; means on said plunger to make and break an electric circuit in connection with said motor; a vertical agitating shaft supported on and operable with said sleeve; a horizontal shaft journaled for rotation at one end on said vertical agitating shaft supported on and
- 20 with the shaft of said motor at its other end; and means to operatively connect said vertical shaft with the last mentioned horizontal shaft, said means consisting of a friction member secured on and rotatable with
- 25 said vertical shaft, and a friction disk secured on and rotatable with said horizontal shaft.
3. A drink mixer comprising a motor having a horizontally disposed rotatable shaft; an abutting horizontal shaft attached to the motor shaft and journaled for rotation with said motor shaft; a vertical shaft mounted and journaled for rotation and adapted to be swung to a position adjacent
- 30 said last mentioned horizontal shaft with friction members to impart the rotary motion of said last mentioned horizontal shaft to said vertical shaft; and agitating blades on said vertical shaft.
4. A drink mixer comprising a horizontal shaft journaled for rotation; a plurality of mixing units mounted adjacent and operatively connected with said shaft, by securing on the end of said shaft a plurality of aligned abutting shafts, one for each unit; 45 bearings for said abutting shafts to hold them in alignment with said first mentioned shaft; an agitator shaft for each unit vertically supported and journaled for rotation; means for imparting the rotary motion of 50 said first mentioned shaft and said abutting shafts to either or all of said agitating shafts when said agitating shafts are swung to a position adjacent said abutting shafts.
5. A drink mixer comprising an electric 55 motor having a horizontal shaft; one or more agitating units attached on one end of said shaft each having a horizontal shaft adapted to be fastened to and in line with said horizontal motor shaft or to the horizontal shaft of a preceding unit; a hollow bearing standard for each unit; a plunger operable in each of said standards; means on each of said plungers to complete an electric circuit and operate said motor; a 60 vertical shaft for each unit; means carried on each of said standards to support the vertical shaft of that standard and to allow it to be swung toward or away from the horizontal shaft of that standard; a friction 65 disk on each vertical shaft to coact with a disk on the horizontal shaft of each unit to impart the rotary motion of said motor shaft to the vertical shaft of each unit when the two disks are brought into contact. 70
- In testimony whereof I have affixed my signature.

JOHN V. BUCKLE.
